(57) **CLAIM**

We claim the ornamental design for a universal integrative mission module interface, as shown and described.

DESCRIPTION

FIG. 1 is a front perspective view of a universal integrative mission module interface;

FIG. 2 is a back perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

The broken lines of the universal integrative mission module interface form no part of the claimed design.

1 Claim, 3 Drawing Sheets
